Primary Examiner — Daniel D Bui(74) *Attorney, Agent, or Firm* — Weber Rosselli & Cannon LLP(57) **CLAIM**

The ornamental design for a solar module, as shown and described.

DESCRIPTION

FIG. 1 is a top perspective view of a solar module, showing our new the design;

FIG. 2 is a top plan view thereof;

FIG. 3 is a left side elevation view thereof;

FIG. 4 is a right side elevation view thereof;

FIG. 5 is a front elevation view thereof;

FIG. 6 is a back elevation view thereof; and,

FIG. 7 is a bottom plan view thereof.

Applicant reserves the right to amend the claimed invention by showing in solid lines any and all features or portions thereof originally shown in broken lines and/or by showing in broken lines any and all features or portions thereof originally shown in solid lines.

1 Claim, 3 Drawing Sheets(56)
